HEADRAIL AND VALANCE BRACKET

Walter J. Stuber and John J. Di Lenno, Philadelphia, Pa., assignors to Carey McFall Company, Philadelphia, Pa., a corporation of Pennsylvania

Application May 22, 1940, Serial No. 336,668

2 Claims. (Cl. 156—17)

This invention relates to head casings for Venetian blinds; and one of the objects of the present invention is to provide a casing enclosed on three sides and both ends, leaving the bottom open for free operation of the blind while fully concealing all the mechanism employed for raising, lowering and tilting the blind.

Another object of the invention is to provide a head casing wherein the head rail, which supports the operating mechanisms of the blind, forms one of the side closures of the casing, for example the top, and wherein the front and back closures are freely removable to expose the operating mechanisms on the head rail without disturbing the head rail.

Another object of the invention is to provide a novel form of back closure plate which, due to its inherent characteristics, requires no screws or equivalent means for retaining it in place and which, while normally retained firmly in position, may be readily removed when desired.

Another object of the invention resides in a novel form of end bracket for supporting the head rail, the back closure plate and the front closure plate, and which constitutes the end closure plates for the head casing.

Another object of the invention is to provide a novel means for supporting the front closure plate, whereby it may be moved to one position to expose the operating mechanism without removal from the head casing or may be completely removed from the head casing, if desired.

The structure forming the subject matter of the present invention will be fully disclosed hereinafter, reference being had to the accompanying drawings of which:

Fig. 1 is a rear elevation of the blind assembly installed in an opening adapted to be covered by the blind;

Fig. 2 is a transverse sectional elevation taken on the line 2—2, Fig. 1;

Fig. 3 is an inverted sectional plan view taken on the line 3—3, Fig. 2;

Fig. 4 is a sectional elevation taken on the line 4—4, Fig. 2;

Fig. 5 is a perspective view of one of the end brackets, showing the one end of the back plate supported thereby;

Fig. 6 is a perspective view of the other end bracket, illustrating the opposite end of the back plate mounted therein;

Fig. 7 is a detached perspective view of the back plate;

Fig. 8 is a view similar to Fig. 2 showing a modified form of front plate; and

Fig. 9 is a view similar to Fig. 8 showing the front plate and head rail being removed.

As viewed from the inside of a room in which the blind is installed, at one of the windows for example, Fig. 5 illustrates the left-hand end bracket 1 and Fig. 6 illustrates the right-hand end bracket 2, which, as noted above, constitute the end closures for the head casing as a whole. The head rail 3, as shown in Figs. 1 and 2, constitutes the top closure plate for the head casing of which the back plate is illustrated at 4 and the front plate at 5, in Fig. 2.

Each of the end brackets 1 and 2 comprises a plate 6 having an inturned vertical flange 7 along its back edge and an inturned horizontal flange 8 along its top edge. The plates 6 and the flanges 7 and 8 in each instance may be provided with openings 9 by which the end brackets may be secured to the inner face of the side rails of a window frame, the front faces of the side rails, or the under-surface of the top rail of said window frame.

Spaced below and extending parallel to the top flange 8, each bracket is provided with a shelf 10 for supporting the top rail 3 of the blind. As shown in Fig. 4 the shelf 10 in each instance is provided with an upturned flange 11 which is welded, riveted or otherwise secured to the plate 6 of the end bracket. As shown in Figs. 5 and 6, the shelf 10 in each instance extends forwardly substantially from the rear flange 7 and terminates short of the front edge 12 of the end plate 6.

Pivoted at 14 adjacent the lower front corner of each of the end brackets 1 and 2 is a front plate or valance holder 15. Each of said holders 15 comprises a body portion 16 lying in a plane parallel to and in contact with the outer face of the end plate 6 and is provided with an in-turned flange 17 which normally is shaped to conform to the front face of the front plate 5.

The lower end of the flange 17, in each instance, is bent backwardly and upwardly, as indicated at 18, to provide a pocket 19 for receiving and holding the lower edge 20 of the front plate 5. The upper end of the flange 17, in each instance, is bent backwardly, as indicated at 21 to embrace the upper edge 22 of the front plate 5. The portion 21 is provided with an indentation 24 which is adapted to snap behind the upper edge 22 of the front plate 5 and maintain the front plate firmly in the carriers or holders 15, 15, to prevent accidental displacement of the front plate when the same is moved from its fully enclosing position,

illustrated in Fig. 2, to a position exposing the interior of the head casing in which the pivoted holders 15, 15 assume the positions illustrated in Figs. 5 and 6 respectively.

As shown in Figs. 2, 5 and 6 the front edge 25 of the shelf 10 is spaced inwardly from the front edge 12 of the end plate 6 to accommodate the front plate 5 therebetween and to prevent accidental displacement inwardly of the valance 5.

The indentation 24 in the inturned portion 21 of each valance holder 15 cooperates with a corresponding depression 26 formed in a resilient tongue 8a on and forming the forward portion of the top flange 8 of each of the end brackets 1 and 2, adjacent the front edge thereof, to form a resilient catch structure adapted to maintain the holders 15 in the position shown in Fig. 2, to retain the front plate 5 in casing-closing position.

Parallel to the rear flange 7, in each instance, the end brackets 1 and 2 respectively are provided with a flange 27 which is spaced from the rear flange 7 a distance slightly in excess of the thickness of the metal of which the back plate 4 is composed.

As shown in Figs. 5, 6 and 7 the back plate 4 is of a concavo-convexed cross-section and its overall thickness x measured from a plane tangent to the crown y of the convexed face 4a to the parallel common plane of the side edges z , z of the concaved face 4b is substantially greater than the thickness t of the metal of which the plate 4 is composed. Therefore, by flexing the opposite ends of the plate 4 transversely and converting the cross-section of the ends from the concavo-convexed form shown in Fig. 7 to a substantially flat form, after the end brackets 1 and 2 have been installed in position in or at a window frame, said ends may be readily inserted in the slots or openings 28 formed between the flanges 7 and 27.

The plate 4, due to its peculiar structure, may be flexed longitudinally to facilitate the insertion of the opposite ends thereof in the slots 28, 28 respectively, and, when released, the back plate will assume a rectilinear state as a result of the structure inherently reassuming its concavo-convexed cross-sectional shape when unrestricted.

By reason of the fact that the opposite ends of the back plate 4 are confined within the slots 28, 28 between the flanges 7 and 27 the attempt of the end portions of the plate to reassume a normal concavo-convex cross-section within the slots 28 causes the ends to frictionally bind against and between the flanges 7 and 27 and thereby retain the plate 4 firmly in position, at the same time permitting said plate to be readily removed by merely flexing said plate longitudinally intermediate the end brackets 1 and 2, which will withdraw or permit the withdrawal of the opposite ends of the back plate from the retaining slots 28, 28.

As shown in Fig. 2, the front plate extends the full distance from the top flanges 8 of the end brackets 1 and 2 to the lower edges 29 of the end plates 6, which lower edges are bent inwardly as indicated at 30 to form relatively narrow stiffening flanges along the lower edges of 70 the end brackets.

The head rail 3 extends substantially from the back face 31 of the front plate 5 to the back flanges 7, 7, thereby fully enclosing the top of the head casing.

The back plate 4 extends substantially from the lower face 32 of the top rail 3 to a point short of the lower edges 29 of the end plates 6, 6. The depth of the back plate 4 may vary in accordance with the mechanism used for raising, lowering and tilting the blind and, if necessary, may extend down to the lower edges 29 of the end plates 6.

The flanges 27 are turned inwardly, as indicated at 33, 33 to embrace the upper and lower edges of the back plate 4 to prevent vertical shifting of said plate relative to the end plates 6, 6. Each of the flanges 27 is provided with a body flange 34 which may be screwed, riveted, welded or otherwise secured to the end plates 6, 6.

In order to prevent the head rail 3 from "walking" outwardly along the supporting shelves 10, 10, a latch 35 is provided below each shelf, with 20 a lip 36 extending upwardly through a slot 37 in the shelf 10 into a recess 38 formed in the lower surface of the head rail 3. Each latch 35 is pivoted at 39 to its associated end plate 6 and is provided with a forwardly projecting finger grip 40 by which it may be moved from its locking position, shown in full lines in Fig. 2, to its head rail releasing position, shown in broken lines in said figure.

In order to prevent accidental displacement of the latches 35, each latch is provided with a small protuberance 41 which is adapted to resiliently project into a hole 42 formed in the end plate 6. The resilient character of the latch provides for flexing of the same to release the protuberance 41 from the hole 42, when the latch is deliberately moved from its full line position to its broken line position in Fig. 2.

As shown in Fig. 1 the tilt rail 45 to which the ladder tapes 46, 46, supporting the slats 47 and bottom rail 48 of the blind, is pivotally supported at its opposite ends in brackets 49 and 50, which are secured, in the present instance, to the underside 32 of the head rail 3.

The bracket 50 carries the tilting mechanism 51, while the bracket 49 carries the locking mechanism 52 for the elevating cords 53 and by which the blind may be raised and lowered and maintained at various elevations in the usual manner.

It will be noted that the back plate 4, as shown in Fig. 1 extends downwardly a sufficient distance to completely conceal the raising, lowering and tilting mechanisms. In a like manner the front plate 5 and end plates 6 extend downwardly a sufficient distance below the under-surface of the head rail 3 to conceal the operating mechanisms completely from the front and ends of the head casing.

The front plate 5, as shown in Figs. 2 and 3, is of a wooden construction and may conform on its front face with the trim molding around the window frame. However, as shown in Figs. 8 and 9, the front plate 5a may be composed of a metal plate provided with an up-and-inturned flange 54, while the upper edge of the plate 5a may be provided with an inwardly and downwardly extending flange 55 spaced from the plate 5a a distance corresponding substantially to the thickness of the wooden valance 5, the lower edge of the flange 55 being disposed below the front edge 25 of the shelves 10 to prevent the front plate from being accidentally moved inwardly out of its proper position in the head casing.

We claim:

1. A Venetian blind head casing comprising a pair of end closures, each provided with a slot

adjacent its rear edge, and a back plate of normally concavo-convex cross-section having its opposite ends respectively mounted in said slots with the crown of the convexed side and the edges of the concaved side bearing against the opposite sides respectively of said slots.

2. A Venetian blind head casing comprising a pair of end closures, each provided with a slot adjacent its rear edge, a back plate of normally

concavo-convex cross-section having its opposite ends respectively mounted in said slots with the crown of the convexed side and the edges of the concaved side bearing against the opposite sides respectively of said slots, and means extending across said slots to limit movement of the back plate longitudinally of said slots.
